UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

WIRE-WORKING MACHINE.

Application filed April 14, 1922. Serial No. 552,768.

This invention is a wire working machine, the object being to so fashion the wire as to render the same available for use in binding packing boxes and other shipping packages.

In the art pertaining to shipping packages it is desirable to utilize wire as a binder; and it is desirable, also, to apply the wire under tension to said packages, and while said binder is under tension to lock together the meeting end portions of the binder, usually by twisting the same. To apply the wire with facility, a suitable implement is required for the performance of the functions of tensioning the wire binder and of locking the same, and to this end the wire is provided adjacent an end portion, or adjacent both end portions, with a shoulder or shoulders whereby in the act of assembling the wire relatively to the package and to the implement, said wire is positioned in a part of the implement for the shoulder of the wire to co-operate with the implement in a manner to prevent the wire from slipping when tension is applied thereto.

The machine of this invention embodies means whereby the wire is deformed to produce a shoulder or shoulders thereon concurrently with the operation of cutting the wire to a length suitable for use on shipping packages of a predetermined cross sectional dimension.

In a practical embodiment of the invention, I employ co-operating swaging dies on an anvil and a plunger for the production of a flattened and shouldered portion on a round wire, the resulting deformation of the wire producing a shoulder adjacent an end portion of the wire. Said dies co-operate to sever the wire adjacent the deformation, and the cutting operation taking place concurrently with the swaging operation.

It is desirable to produce a plurality of deformations on the same length of wire, one deformation being adjacent one end portion of the cut length and the other deformation adjacent the opposite end portion of the same wire length, and to these ends, I provide co-operating dies in multiple on the anvil and the plunger, together with suitable provision on the plunger, for cutting the wire at a point intermediate the multiple swaging dies.

Other functions and advantages of the

invention will appear from the following description taken in connection with the drawings, wherein—

Figure 1 is an elevation of mechanism for cutting a continuous wire into suitable lengths and for producing deformations thereon, said mechanism being shown in connection with an appropriate form of straightening means whereby the wire from a coil is straightened, cut to length, and deformed in a continuous operation.

Figure 2 is an enlarged sectional elevation through the coacting swaging dies provided on an anvil and a plunger, respectively, said dies acting to cut the wire at a point adjacent the deformation resulting from the swaging action.

Figure 3 is a view in elevation of a cut length of the deformed wire, with a flattened and shouldered portion adjacent one end, said cut length of wire being the product of the operation of the dies illustrated in Figures 1 and 2.

Figure 4 is a plan view of the deformed cut length of wire shown in Figure 3.

Figure 5 is an elevation, partly in section, of multiple swaging dies and of co-operating cutting dies for producing cut lengths of wire with deformations adjacent the respective ends of the same length of each wire.

Figure 6 is a plan view of the cut length of wire with deformations adjacent its respective ends, the same being the product of the dies shown in Figure 5.

Figure 7 is a view illustrating the action of the multiple swaging dies in producing one cut length of wire with two deformations concurrently with the production of a portion of another cut length of deformed wire, with a complete line of severance intermediate the two cut lengths.

Figure 8 is a cross section through the deformation produced by the action of the swaging dies, the plane of section being on the line 8—8 of Figure 3.

Figure 9 is a view in side elevation of one form of the machine.

Figure 10 is a front view thereof.

Figure 11 is a detail sectional view of one form of clutch mechanism.

Figure 12 is a detail view of the wire receiving plates.

Figure 13 is a detail of the clutch lever. As shown in Figures 1 and 2 of the draw-

ings, a plunger A is fitted for vertical reciprocating movement within a suitable guide-way b provided on a fixed head B, at the bottom of which head is fixedly held an anvil C, the latter being positioned in alignment vertically with said plunger.

D E are the co-operating swaging dies, the die D being fixedly held on the anvil B, whereas die E is attached in a suitable manner to the plunger at the lower part thereof, whereby said dies D E are positioned in facing relation one to the other, and the die on the plunger is movable relatively to the die on the anvil. The opposing surfaces of the two dies D E are fashioned to mutually co-operate in swaging a wire round in cross section so as to deform the latter by flattening said wire and producing a shoulder thereon, the wire being indicated at X in Figures 3 and 4, the deformed portion thereof at α and the shoulders at α' .

The under face e of the movable swaging die E protrudes below the under face of the plunger, see Figures 1 and 2, whereas the upper face d of the stationary swaging die D is above the plane of the corresponding face of the anvil C, so that in the down-stroke of the plunger and the die E the interval between the faces d e is less than the interval between the plunger and the anvil, whereby dies D E co-operate in acting on the round wire X to compress the metal so as to produce the flattened or deformed part α with the shoulders α' at the ends of the flattened portion. The flattened portion α is of a width exceeding the diameter of the wire, whereas the thickness of said flattened portion α is less than the diameter of said wire, as will be understood by reference to Figures 3, 4 and 8.

F is a cutting die carried by the plunger in a position parallel to the swaging die E and at a desirable distance from the same. The cutting die is fixedly attached to the plunger for vertical movement therewith, and said die F is shown as having a cutting edge f positioned to shear past the edge f' of the anvil, whereby the die F co-operates with anvil C in severing the wire concurrently with the operation of swaging the wire, thus producing at one operation a piece of wire deformed as required and cut to the desired length.

The machine illustrated in Figure 1 is adapted for straightening the wire as it is drawn from a coil. Said machine includes a rotary head G, driven by a pulley and belt, and equipped with appropriate means, such as the usual rolls, for acting on the wire to straighten the same. The wire from the coil is directed into the guide h, and advanced or fed at the desired speed by feed rolls H, between the swaging dies, whence the wire passes into the wire receiving plates I, operable intermittently as usual

for dropping the cut lengths of wire into wire holding receivers or trough which may be said to constitute a bundling mechanism J, as usual in the art. The motion of the wire receiving plate is timed with the drive shaft a having the usual eccentric motion for imparting reciprocating movement to the plunger by which the upper swaging die and the cutting die are operated.

The shaft a by which the plunger A is operated is driven intermittently to effect the reciprocating motion of upper die E and cutter F, but said plunger, die and cutter are normally raised and at rest during the operations of straightening the wire and of feeding a length of wire into a wire receiving space or socket comprised by complementary grooves i provided in the contiguous edges of a pair of horizontal plates i' i' constituting the wire receiving and holding means I. Said plates i' are provided with oblique slots i" in which are fitted studs j of supporting arms J' which are rigid with certain of the wire receivers j', and with said slotted plates is associated a lever I', the lower end of which is provided with a head k that engages with plates k' on the wire receiving plates i' for imparting sliding motion to the latter, whereby the plates are relatively moved so as to open and close by the studs j working in the oblique slots of said plates.

On shaft a is a loose pulley L, which runs continuously, being driven by a belt (not shown). Co-operating with the shaft a and pulley L is a clutch M, which is shown as a pin slidably fitted in a groove m of the shaft a and is received in a socket m' provided in a hub l of said pulley L. The clutch pin is impelled by a spring m toward the socketed part of the pulley, but said clutch pin is held free from engagement with the socket by a clutch lever O, the latter having a wedge member o fitting in a groove of the clutch pin. Said clutch lever O is fulcrumed at l' on the fixed standard or head B, and to the longer arm of said lever is attached the trip wire P, the latter extending to a wire-operated tripping device designated in its entirety at Q. As usual in the art, the tripping device embodies a slidable rod q loosely retained in a groove of one of the receiving plates i', a stop collar q' fixedly held on said rod q, a stop arm q" fixedly attached to one of said plates i' and positioned in the path of stop collar q', and a spring q" fastened to an upstanding part of the stop collar. The trip wire P is connected to the stop collar or to the trip rod, and when the required length of straightened wire is fed into position between the plates i' of the wire holding and receiving means I, then said length of straightened wire imparts movement to the trip rod q for pulling on the trip wire P and operating the lever O, the wedge of which is

withdrawn from the notch of the clutch pin, whereupon the spring snaps the clutch pin lengthwise of the shaft and into the socket of hub l , whereby the pulley drives the shaft

- 5 a for operating the upper die and the upper cutter. This operation of the die and the cutter takes place during a half revolution of shaft a , and during the remainder of said revolution of shaft a the wedge of the clutch 10 engages with the clutch pin and retracts the clutch from the pulley, leaving the plunger, die and cutter in a raised position, whereas the driving rolls H and wire straightener G are in operation continuously, with the plunger operated quickly and at intervals as determined by the feed of the wire into the plates i' of the receiving means I .

The operation is apparent. The wire is drawn from the coil and through the straightening head by the feed rolls, and advanced to the required position between the swaging dies and cutting dies, whereupon the plunger descends to bring the swaging dies together and for the cutting die to shear past the edge of the anvil, as a result of which the wire is cut and deformed at one operation. The plunger ascends and the wire is fed between the grippers, whereupon the plunger again descends for closing the swaging dies and operating the cutting dies to swage and cut a length of wire, the grippers being opened to drop the previously cut length of wire into the bundling device.

The dies of Figures 1 and 2 operate as described to produce a single wire cut to a desired length and deformed adjacent one end portion, as in Figures 3 and 4; but it is desirable to produce a wire X' cut to a desired length and provided with deformations a a^2 , adjacent the opposite ends of the same wire X' , as shown in Figures 7 and 8. To this end I provide swaging dies in multiple as in Figure 5 and a cutting die for cutting out a short section of the wire intermediate 150 two of the deformations on the lengths X' X^2 , see Figure 7. The multiple swaging dies are indicated at D E and D' E' provided on the anvil C' and the plunger A' , the movable dies E E' being carried by the plunger, whereas the stationary dies D D' are fixedly 155 held on the anvil. The cooperating dies D E are provided with working faces d e , as heretofore described, and the other pair of dies, D' E' , are provided with similar faces d' e' , the dies D' E' being positioned alongside the dies D E and suitably spaced with respect thereto.

Intermediate the movable swaging dies E E' on the plunger is a single cutting die K provided with two cutting edges k k' adapted to co-operate with shear cutting edges m m' on the anvil C' , and to operate in the space m^2 of said anvil.

In the operation of the double swaging 160 dies and the cut out cutting die of Figure

5, the wire from the coil passes through straightening means and between the dies when the upper dies are raised with respect to the lower dies, but on the descent of the plunger A' the dies D E produce a deformation and the dies D' E' produce a second deformation, whereas the cutter K is operated for its edges k k' to shear past the edges m m' for cutting out a relatively short section of the wire as at o in Figure 7, where by the lengths X' X^2 are swaged at a^2 a^3 , and the wire is cut out at o at one operation, as a result of which each length of wire is formed at successive operations with two deformations a a^2 , see Figures 7 and 8, so one near each end, and said wire is cut into pieces of appropriate length X' X^2 .

Having thus fully described the invention, what I claim as new and desire to secure by Letters Patent is:

1. In a machine for making wire package binders, the combination with wire feeding means, wire-straightening means, and a co-operating stationary anvil and reciprocating member in spaced relation to said feeding means, of a plurality of deforming dies carried respectively by said stationary anvil and said reciprocating member, said dies being mutually co-operable on a length of wire for producing thereon a deformation bounded by a holding shoulder, and a plurality of cutting members one on the stationary anvil and the other on the reciprocating member, said cutting members being mutually co-operable and acting concurrently with the deforming dies for severing the wire adjacent the deformation produced on said wire by the action of said dies, said co-operating cutting members being in spaced relation to said deforming dies where by a short length of wire is left intact between the severed wire end and said deformation.

2. In a machine for making wire package binders, the combination with wire feeding means, and wire-straightening means, of a stationary anvil one face of which constitutes a stationary cutting means and presents a shearing edge, a deforming die carried by said anvil and the face of which die is positioned in spaced relation to said shearing edge, a reciprocating member movable relatively to said anvil, a second deforming die carried by said reciprocating member and positioned for the face of said die to co-operate with the first deforming die in acting upon a wire to cross sectionally deform said wire and to produce a holding shoulder next to said deformation, and a second cutting member carried by said reciprocating member and positioned in spaced relation to the first deforming die, said second cutting member being in shearing relation to the shearing edge on the stationary anvil and co-operating therewith for severing.

ing a wire at a point distant from said deformation and holding shoulder so as to leave a short length of wire between said severed wire end and the deformation.

5. 3. In a machine for making wire package binders, the combination with wire feeding means, wire-straightening means, and co-operating stationary anvil and reciprocating members in spaced relation to said wire feeding means, of a set of multiple swaging dies carried by said anvil, a second set of multiple swaging dies movable with said reciprocating member, said multiple dies of the two sets being in co-operative relation 10 one to the other for producing a plurality of relatively spaced deformations on a wire, and a plurality of cutting members one carried by the anvil and the other by the reciprocating member, said cutting members 15 being spaced relatively to swaging dies of the two sets and actuated concurrently with said swaging dies and operating in a plane intermediate the two sets of swaging dies for severing a wire at a distance from each 20 of said deformations produced on the wire by the action of said two sets of deforming dies.
4. In a machine for making wire package binders, the combination with a stationary anvil, and a moving member reciprocable 25 relatively thereto, of wire feeding means operable for feeding wire between said anvil and said reciprocable member, a set of multiple swaging dies on the anvil, a second set of multiple swaging dies on the reciprocable member, the faces of said dies being

in facing relation and mutually co-operating for producing a plurality of relatively spaced deformations on a wire, and cutting members carried respectively by the anvil 40 and the reciprocable member, said cutting members being intermediate the dies of the two sets and having shearing relation one to the other for severing wire in a plane intermediate the deformations produced 45 thereon by said swaging dies.

5. In a machine for making wire package binders, an anvil provided with a plurality of shearing edges, a set of multiple swaging dies carried by said anvil, said dies being 50 at the respective sides of the shearing edges and spaced relatively thereto, a reciprocating member, a second set of multiple swaging dies carried by the reciprocable member, the faces of the dies of the second 55 set being in facing relation to similar faces of the dies of the first set and the two sets of dies mutually co-operating to produce a plurality of relatively separated deformations on a wire, means for feeding a wire 60 intermediate the two sets of dies, and a cutter member carried by the reciprocable member and positioned intermediate the dies of the second set and occupying a shearing 65 relation to the plurality of shearing edges on the anvil whereby the cutting elements co-operate in severing a wire in a plane intermediate the deformations produced on said wire by the two sets of deforming dies.

In testimony whereof I have hereto 70 signed my name this 13th day of April, 1922.

SPENCER C. CARY.
